UNITED STATES PATENT OFFICE.

CHARLES H. SIMERSON, OF WEST HOBOKEN, NEW JERSEY.

CHECK-CONTROLLED DEVICE.

1,081,782.

Specification of Letters Patent. Patented Dec. 16, 1913.

Application filed March 24, 1913. Serial No. 756,387.

To all whom it may concern:

Be it known that I, CHARLES H. SIMERSON, a citizen of the United States, residing at West Hoboken, in the county of Hudson and State of New Jersey, have invented certain new and useful Improvements in Check-Controlled Devices, of which the following is a specification.

This invention has relation to check controlled devices; and consists in the novel features hereinafter described and claimed.

An object of the invention is to provide a check controlled device of simple and durable structure which is especially adapted to be used in conjunction with pumps for dispensing gasoline or similar liquids, although the device may be used in conjunction with dispensers for other commodities or articles.

A further object of the invention is to provide in a device of the character indicated means for preventing a check or coin of a size smaller than that intended to be used from engaging the operating parts of the device and moving the same.

A still further object of the invention is to provide in a device of the character indicated a shaft adapted to be operatively connected with the dispensing machine or apparatus and a lever mechanism for holding the shaft against rotation in one direction. This lever mechanism is provided with a pocket adapted to receive a check of predetermined size. When the check is deposited in the pocket the lever is moved to a position whereby the shaft is released or rendered

free to turn in either of two directions as the shaft rotates to operate the dispensing machine it eventually operates mechanism with which the check controlled device is provided for moving the pocket to check releasing position whereby the check is permitted to fall from the mechanism into the body of the casing inclosing the same. Means are provided for returning the parts to normal positions and a member is so mounted as to strike the check when the pocket is moved to check releasing position whereby the check is positively ejected from the pocket.

Means is provided for limiting the rotation of the shaft in an operative direction to a predetermined number and this means may be adjusted so that a quantity of the commodity dispensed may be regulated. The device is also provided with means for promptly bringing the pocket to check releasing position in the event that an attempt

is made to rotate the shaft in the direction opposite to that in which it rotates when operating the dispensing machine.

A further object of the invention is to provide means for registering the number of times that the pocket is moved to check releasing position.

A still further object of the invention is to provide means for sounding an alarm or signal each time the pocket is moved to check releasing position.

With these and other objects in view, the invention consists in certain novel features of construction as hereinafter shown and described, and then particularly pointed out in the claims and in the drawings illustrative of the preferred embodiment of the invention.

In the drawings:—Figure 1 is a side elevation of the device with parts broken away. Fig. 2 is an edge elevation of the same. Fig. 3 is an enlarged elevation of the device with a portion of the casing removed showing the pocket in check receiving position. Fig. 4 is a similar view showing the pocket containing a check whereby the shaft is released. Fig. 5 is a similar view showing the pocket in check releasing position. Fig. 6 is a horizontal sectional view on the line 6—6 of Fig. 3. Fig. 7 is a similar view on the line 7—7 of Fig. 3. Fig. 8 is a similar view on the line 8—8 of Fig. 3. Fig. 9 is a vertical sectional view on the line 9—9 of Fig. 3. Fig. 10 is a similar view on the line 10—10 of Fig. 3.

Corresponding and like parts are referred to in the following description and indicated in all the views of the accompanying drawings by the same reference characters.

The check device comprises a casing 1, which may be of any suitable design or pattern. A shelf 2 is located in the upper portion of the casing and is provided with openings 3 and 4. The casing 1 is provided in its top with an opening 5. The opening 3 is somewhat longer than the opening 4 and is located more nearly under the opening 5. A block 6 is slidably mounted in the casing 1 between the shelf 2 and the top of the casing and is provided with an opening which extends vertically through the same. Flanges 7 depend from the shelf 2 and surround the opening 4. A chute 8 depends from the shelf 2 below the opening 3.

When the device is operated, a check is inserted through the opening 5 into the

block 6. The block 6 is then moved longitudinally along the space between the shelf 2 and the top of the casing 1. If the check is of the proper size it will be carried by 5 the block to the opening 4 through which it will fall between the flanges 7. If the check is not of the proper size it falls through the opening 3 and passes down through the chute 8 into the lower portion 10 of the casing without operating the mechanism.

A shaft 9 is journaled in the casing 1 and is adapted to be connected in any suitable manner with the pump or other machine 15 which is to be operated. A ratchet wheel 10 is fixed to the shaft 9 and is located between the sides of the casing 1. A guide 11 is located above the ratchet wheel 10 and a pawl 12 is slidably mounted in the guide 20 11 and is adapted to engage the teeth of the wheel 10. A lever 13 is fulcrumed in the casing 1 and is provided at one end with a pivoted link 14 which is also pivotally connected with the pawl 12. The lever 13 is provided at 25 that end opposite the end thereof at which the link 14 is mounted with a check pocket 15, which is located below the opening 3 and the flanges surround the said opening. A weight 16 is adjustably mounted on the lever 30 13 at one side of the fulcrum thereof and by shifting the said weight the poise of the said lever may be varied or adjusted.

A rod 17 is pivoted in the casing 1 and is provided with an approximately horizontal portion 18 and a vertical portion 19. The said rod is provided at its upper end with a loop 20 which loosely receives the lever 13 in the vicinity of the pocket 15. Guides 21 may be mounted in the casing 1 40 and a rod 22 is slidably mounted in the said guides. The said rod is provided with an eye 23 which receives the vertical portion 19 of the rod 17. A stop 24 is mounted upon the rod 22 at a point between the guides 21 45 and a coil spring surrounds the rod 22 and bears at one end against the stop and at its other end against the guide 21 nearest the rod 17. This spring is under tension with a tendency to hold the eye 23 toward the adjacent guide 21 whereby the portion 19 of the rod 17 is normally held in an approximately vertical position. A spring 26 surrounds the rod 22 between the stop 24 and that guide 21 which is more remote from the 55 rod 17. The spring 26 serves merely as a buffer to check the longitudinal movement of the rod 22.

The rod 17 is provided at a point below its pivot with a weight 27 which has a tendency to hold the portion 19 of the said rod substantially vertical.

A member 28 is pivoted in the casing 1 and is provided with an end portion 29 which normally lies in the path of movement 65 of the teeth of the wheel 10 and the

opposite end of the member 28 is downwardly disposed toward the horizontal portion 18 of the rod 17. A stop 30 is located in the path of movement of the end portion 29 of the said member 28.

A gear wheel 31 is fixed to the shaft 9 and meshes with the gear wheel 32 which is journaled upon a stud 33 located in the casing 1. The gear wheel 31 is of relatively small diameter while the gear wheel 32 is of relatively large diameter. The gear wheel 32 is provided with a series of perforations 34 in any one of which may be positioned a pin 35. An arm 36 is pivoted in the casing 1 and has an end which extends into the path of movement of the pin 35. The other end of the said arm is loosely connected with the horizontal portion 18 of the rod 17. The arm 36 is further provided with a depending finger 37. A counter 38 is located in the casing 1 and its shaft is operatively connected with a plate 39 and which is located in the path of movement of the finger 37. A wire 40 is connected with any part of the casing 1 and a wire 41 is connected with the plate 39. These wires are electrically connected with batteries 42 and a buzzer or alarm 43. When the parts are in their normal positions the pawl 12 is in engagement with the teeth of the wheel 10 and the pocket 15 is in an elevated position under the flanges 7. Thus the shaft 9 is held against rotation in one direction. As soon as a check is deposited in the pocket 15 the said pocket descends so that the lever 13 comes in contact with the lower side of the loop 20. At the same time, the pawl 12 is lifted above the teeth of the wheel 10. Therefore the said wheel and the shaft to which it is attached are free to rotate. As 105 the said parts rotate, the gear wheel 32 is rotated until the pin 35 comes in contact with the arm 36. When this occurs the said arm is swung upon its pivot whereby the portion 18 of the rod 17 is swung in a downward direction, and the portion 19 of the said rod is moved down whereby the pocket 15 is moved to a check releasing position. At the same time the loop 20 strikes the check and ejects the same from the pocket. 110 Thus the machine which is operatively connected with the shaft 9 is operated to dispense the commodity. As soon as the pin 35 passes the end of the arm 36 the spring 25 and the weight 27 come into play and return 120 the parts to their normal positions. If at any time before the pin 35 strikes the arm 36, an attempt should be made to rotate the shaft 9 in a direction opposite to that in which it should rotate to operate the 125 pump, one of the teeth of the wheel 10 will strike the end of the member 28 and the said member is swung down so that it strikes the horizontal portion 18 of the rod 17, and the said rod is moved to bring the 130

5 pocket to check releasing position. Therefore any attempt to make the device repeat or prolong its operation will be frustrated or prevented. By shifting the pin 35 in the 10 perforations 34 the dispensing machine may be caused to deliver any predetermined quantity of the commodity. However, by 15 removing the gear wheel 32 from the stud 33 and turning the same with relation to the gear wheel 31 and replacing it upon the stud the quantity of the commodity delivered 20 may be regulated to a nicety.

As the arm 36 is swung the finger 37 encounters the plate 39 and operates the 15 counter 38. This means is provided for indicating the number of times that the check pocket has been moved to check releasing position. Each time that the finger 37 comes in contact with the plate 39 an 20 electric circuit is completed along the wires 40 and 41 and through the battery 42 and alarm 43. Therefore means is provided for announcing each time that the device is operated. The alarm 43 may be positioned at 25 some distance from the device, and in fact out of hearing to one who operates the device. Therefore a person having supervision of the alarm will be notified when the device is being operated, and if he entertains 30 suspicion that spurious checks are being used, he may examine the contents of the casing after each operation to determine what individual is using such checks to operate the device.

35 Having described the invention what is claimed; is:—

1. Apparatus of the character described comprising a rotatable shaft, a pivoted lever disposed near the same and provided with 40 check holding means, means operated by the pivoted lever to control the rotation of the shaft, a pivoted weight, an approximately L-shaped lever having its vertical arm loosely connected with the pivoted lever to 45 move with relation thereto and strike the check in the check holding means to eject it therefrom and its horizontal arm connected near its free end with the pivoted weight to be held thereby in its normal position, a 50 lower pivoted lever having a loose connection with said horizontal arm, and means driven by the shaft to trip said lower lever.

2. Apparatus of the character described, comprising a rotatable shaft, a lever pivoted 55 near the shaft and provided with check holding means, means operated by the pivoted lever to control the rotation of the shaft, a pivoted weight, a rod connected with the

pivoted weight to be normally held thereby in one position and having loose connection 60 with said pivoted lever for movement with relation thereto to eject a check from the check holding means, and means operated by the shaft to move the pivoted rod in one direction. 65

3. A check controlled device comprising a journaled shaft, a lever fulcrumed adjacent the shaft and having a pocket adapted to receive a check, means carried by the lever for holding the shaft against rotation in one 70 direction when the pocket is in an elevated position, said means adapted to release the shaft when the pocket is in a lowered position, a rod pivotally mounted and engageable with the lever to move the pocket to 75 check receiving and check releasing positions, means operated by the shaft to move the rod and means for varying the interval of movement of the rod with relation to the movement of the shaft. 80

4. A check controlled device comprising a journaled shaft, a lever fulcrumed adjacent the shaft having a pocket adapted to receive a check, means carried by the lever for holding the shaft against rotation in one 85 direction when the pocket is in an elevated position, said means adapted to release the shaft when the pocket is in a lowered position, means operated by the shaft to move the pocket to check releasing position when 90 the shaft rotates in one direction and means for moving the pocket to check releasing position when the shaft is turned in the opposite direction.

5. A check controlled device comprising a 95 journaled shaft, a lever fulcrumed adjacent the shaft and having a pocket adapted to receive a check, means carried by the lever for holding the shaft against rotation in one direction when the pocket is in an elevated 100 position, said means adapted to release the shaft when the pocket is in a lowered position, means operated by the shaft to move the pocket to check releasing position when the shaft is turned in one direction a predetermined number of rotations and means for immediately moving the pocket to check releasing position when the shaft is turned in 105 an opposite direction.

In testimony whereof I affix my signature 110 in presence of two witnesses.

CHARLES H. SIMERSON.
